UNITED STATES PATENT OFFICE

2,571,543

CLOTH TOP SOCK

Walter F. Connor, Lowell, Mass., assignor to Hub
Hosiery Mills, Lowell, Mass., a corporation of
Massachusetts

Application December 6, 1948, Serial No. 63,671

1 Claim. (Cl. 2—240)

1

This invention relates generally to hosiery and more particularly to a sock construction in which the foot, ankle and leg is constructed of knitted material, while the cuff is constructed of woven material.

The primary object of this invention is to make available to the hosiery manufacturer a greatly increased variety of designs in the cuffs of socks. Heretofore hosiery manufacturers have been definitely limited in the designs of the cuffs because of the limitation of the knitting machines, the designs to be incorporated being only those capable of being produced by these knitting machines. In other words, if the knitting machines are used to produce both the foot and all parts of the leg of the sock, only those designs capable of being knitted by the knitting machines can be incorporated in the leg and/or cuff. This invention enables the hosiery manufacturer to avail himself of a very wide variety of woven materials, with an indefinitely large number of designs.

Another object of this invention is to provide a sock construction in which the cuff can be constructed of woven material which is relatively inexpensive, the necessary elasticity in the cuff being accomplished by sewing the cuff with elastic thread so that the cuff is gathered and contracted, it being noteworthy that the woven material need not be of special construction since the elasticity is added thereto according to this invention and the relatively expensive process of weaving elastic threads into the cuff material is eliminated. In this connection, it may be noted that applicant is aware that cuffs having elastic threads woven into the material of the cuff have been proposed prior to this invention, this invention being not concerned with this older and much more expensive means for producing a cuff.

With these objects definitely in view, this invention resides in certain novel features of construction, combination and arrangement of elements and portions as will be hereinafter described in detail in the specification, particularly pointed out in the appended claim, and illustrated in the accompanying drawing which forms a material part of this application, and in which:

Figure 1 is a perspective view of a sock constructed according to this invention and worn with the cuff folded on itself;

Figure 2 is a side elevational view of the cuff 50

and the upper portion of the ankle of a sock, constructed according to this invention;

Figure 3 is a fragmentary horizontal sectional view, taken substantially on the line 3—3 in Figure 2; and

Figure 4 is a vertical sectional view of a cuff represented as worn in Figure 1.

Similar characters of reference designate similar or identical elements and portions throughout 10 the specification and throughout the different views in the drawing.

Referring now to the drawings in detail, this sock includes a foot portion 10 and an ankle 12. A section of material 14 woven from inelastic threads 16 has its ends sewn together at 18 to comprise a cuff. The lower edge of the cuff is sewn, preferably with inelastic thread to the upper end of the ankle 12, as indicated at 20. The threads used to sew the ends of the material 14 together, at 18, need not be elastic.

The cuff so formed is sewn across with elastic thread 22 on a machine with multiple needles, or can be sewn several times across with elastic thread 22 on a single needle machine so as to 25 gather and to contract the cuff. In Figure 3, one possible type of stitching is represented as used in sewing the elastic threads 22 on the material 14, but other types of stitching might 30 well be used to apply the elastic thread to the cuff.

If desired, the edge of the cuff remote from the ankle 12 may be hemmed as indicated at 24 and sewn one or more times, as indicated at 26.

35 It should be clearly understood that the cuff is constructed of inelastic woven material sewn with elastic thread to make the finished product definitely elastic, and it should also be pointed out that the elastic threads 22 need not be regu-

40 larly spaced in relation to the threads composing the inelastic material 14, so that ordinary sewing machines may be used to apply the elastic thread to the material 14 and the task of producing a finished product is greatly reduced.

45 The foregoing will clearly indicate how this invention can be used and further description would appear unnecessary. Minor variations from the embodiment described above and illustrated in the drawing may be resorted to without departure from the spirit of this invention

and the scope thereof should be determined only as limited by a proper interpretation of the terminology used in the subjoined claim.

Having described the invention, what is claimed as new is:

As a new article of manufacture, a sock comprising foot and ankle portions of knitted fabric, and a tubular cuff of woven inelastic fabric stitched to said ankle portion, said cuff including longitudinal pleats extending from end to end thereof and further including a hem on its free end, and longitudinally spaced rows of circumferentially extending elastic stitches in the cuff for yieldingly resisting expansion thereof,

certain of said elastic stitches further securing the hem.

WALTER F. CONNOR.
